UNITED STATES PATENT OFFICE

GEORGE T. JOHNSON AND HARRY W. STERTZBACH, OF COLUMBUS, OHIO, ASSIGNORS
TO THE BUCKEYE STEEL CASTINGS COMPANY, OF COLUMBUS, OHIO

BOLSTER

Original application filed April 13, 1928, Serial No. 269,692. Divided and this application filed January 3, 1929. Serial No. 330,068.

This invention pertains to railway rolling stock, and more particularly to an improvement in railway cars, and the present application is a division of our application Serial No. 269,692, filed April 13, 1928.

5 This divisional application relates to the construction of heavy capacity cars of the type in which the bolster is within the body cavity, in contradistinction to cars of the type having the bolster positioned beneath the body. Inside bolsters have heretofore usually consisted of two trusses integrally united at their inner ends by a member of rectangular form placed over the center sill of the car.

10 The rectangular member, unless its entire web is a continuous or uninterrupted plate, or unless it is provided with struts or braces extending between its diagonally opposite corners, does not successfully resist deformation in the plane of the rectangle, when there is an unsymmetrical vertical loading condition imposed on the structure as an entirety.

15 Like in our parent application, it is the object of this invention to overcome this difficulty, and to produce a bolster of truss form throughout, having the portion immediately over the center sill region of the car so arranged that diagonal elements are called upon to resist deformation in this part of the bolster, when the body is not uniformly loaded, or the rolling of the car causes the side bearings to come into action.

20 A further object is to provide a bolster of this character in which the central portion of the same is provided with a substantially conical reinforced portion designed to take strains from substantially all directions.

25 With the foregoing objects outlined and with other objects in view which will appear as the description proceeds, the invention consists in the novel features hereinafter described in detail, illustrated in the accompanying drawings, and more particularly pointed out in the appended claims.

45 Referring to the drawings,

Fig. 1 is a fragmentary view partly in elevation and partly in section, of a car body and bolster therein, showing one embodiment of the invention.

Fig. 2 is a bottom view of one-half of the 50 bolster.

Fig. 3 is an elevation of the central portion of the bolster, shown resting on the center sill.

Fig. 4 is a similar view of a modification.

Fig. 5 is a bottom plan view of the medial portion of the bolster shown in Fig. 4.

Fig. 6 is a view similar to Figs. 3 and 4, of another embodiment of the invention.

Fig. 7 is a bottom plan view of the medial portion of the bolster shown in Fig. 6. 60

Referring particularly to Figs. 1 to 3 inclusive, 1 designates the side of a car body consisting of metal plates having a reinforcing channel bar 2 secured along their upper edges, and an angle bar 3 secured along their lower edges, the outer edges of the floor plates 4 being also secured to the angle bar 3, as shown, and as will be understood.

70 The medial portion of the floor plates is supported by the center sill, which consists essentially of a pair of parallel channel bars 5 and a cover plate 6 secured thereon. The bolster 7, forming the main feature of the present invention, rests directly upon the floor plates, with its ends abutting against the opposite sides of the body. This bolster is preferably a one-piece casting formed on both of its faces with lateral marginal flanges 8, through which rivets are fastened to secure it firmly to the car sides and floor. On the top of the bolster, at each end thereof, is a central longitudinal rib 9 to which is secured the lower end of a wing plate 10, which is also secured to the car side by any suitable means, 80 such as rivets.

75 Primarily, the bolster is a central vertical web which has in addition to its marginal flanges 8, other flanges hereinafter referred to. The web, in the interest of lightness, is 85 90

not continuous or solid, but is provided with openings 11 separated by diagonal struts 12 which join the top and bottom portions of the bolster. These struts are not arranged in a haphazard manner, but they are specially arranged to minimize the effect of shifting of the load in the car, and to furnish the requisite strength. Due to the diagonal arrangement of the struts, most of the openings 10 11 are of triangular form, but the central openings 13 are of other forms, due to the fact that a strut 14, of special shape, unites the medial portions of the upper and lower bars of the bolster. The strut 14 consists of 15 an upper vertical portion 15 that is branched at its lower end to provide diverging legs 16 which terminate immediately above the channel bars 5 of the center sill.

All of the struts including the medial one 20 14, are provided at their opposite sides with reinforcing flanges 17, preferably of continuous form, and extending from the marginal flange 8 at the bottom of the bolster, to the same flange at the top of the bolster.

25 The flange 8 at the bottom of the bolster is provided with widened or projecting portions 18, 19, at four properly spaced points, to provide an ample surface for the attachment of side bearings 15. If the side bearings are to be located near the sides of the car body at the outer side of the truck wheels, they will be attached to the extensions 19. On the other hand, if they are to be located at the inner side of the wheels, and near the 30 central sill, they will be attached to the extensions 18. At this point it may be noted that the extensions are arranged directly below the point of joining the struts to the bottom of the bolster, so that any strains imparted to the extensions 18, 19 will be transferred to the struts, and vice versa.

In the form shown in Figs. 4 and 5, the strut 20, which corresponds with the strut 14 in Fig. 3, terminates at its lower portion in 45 diverging webs 21 which are concaved horizontally, and these webs are reinforced by longitudinally extending webs 22 and transverse webs 23. Webs 22, as well as the webs 23 diverge downwardly.

50 It may be also seen from Fig. 5 that the medial portion of the bottom of the bolster is provided with oppositely extending lugs 24 to accommodate this special form of webs at the central portion of the bolster.

55 The modification shown in Figs. 6 and 7 differs from that shown in Figs. 4 and 5 in having the lower end of the vertical strut member 25 developed into a conical or bell-like web 26 of elliptical form at its base, and 10 the bottom of the bolster is widened at 27, to correspond with said elliptical base. An elliptical opening 28 is formed in the bottom of the bolster, and within the bell the strut 25 terminates in a cruciform foot 29.

60 From the foregoing it is believed that the

construction and advantages of the invention will be readily understood by those skilled in the art, and we are aware that various changes may be made in the details disclosed without departing from the spirit 70 of the invention, as expressed in the claims.

What is claimed and desired to be secured by Letters Patent is:

1. An inside bolster for car bodies of truss form from end to end, and provided at its 75 medial portion with a centrally disposed strut having downwardly diverging portions united with the bottom of the bolster.

2. A one-piece inside bolster for car bodies 80 of truss form from end to end, and provided at its medial portion with a vertical strut having downwardly diverging branches, said strut joining the top and bottom portions of the bolster.

3. An inside bolster for car bodies having 85 diagonal strut members joining the top and bottom portions of the bolster, a vertical strut having its upper end united with the medial portion of the bolster at the point of meeting of a pair of diagonal struts, the vertical strut merging at its lower end into diverging portions which connect the vertical strut to the bottom of the bolster.

4. An inside bolster for car bodies of truss form from end to end, and provided at its 90 bottom at each side of its medial portion with a pair of transverse extensions adapted for attachment to either inside or outside bearings.

5. In a car construction, a center sill, and a 100 bolster having strut members extending diagonally upward from the sides of the sill and terminating in a common strut that is united with the top of the bolster.

6. In a car construction, a center sill, and 105 an inside bolster having diagonal strut members extending from the bottom of the bolster, and meeting at the top of the same over the center sill, and a vertical strut member extending downward from the meeting point 110 of the diagonal strut members, and having its lower end divided into diverging members extending to the bottom of the bolster.

7. An inside bolster for car bodies, provided at its medial portion with a downwardly 115 flared reinforced annular web.

8. An inside bolster for car bodies, provided at its medial portion with a downwardly flared reinforced annular web, the bottom of the bolster having an opening leading into 120 the cavity formed by said web.

9. An inside bolster for car bodies, provided at its medial portion with a downwardly flared reinforced annular web, the bottom of the bolster having an opening leading 125 into the cavity formed by said web, and a cruci-form reinforcement arranged in the cavity and joining the web to the bottom of the bolster.

10. A one-piece inside bolster for car 130

bodies of truss form, from end to end, and provided at its medial portion with a vertical leg which branches at its lower end into diverging portions that unite the vertical
5 strut with the bottom of the bolster, the bolster having marginal flanges at opposite sides thereof, and the struts having oppositely extending flanges merging into the marginal flanges.

10 In testimony whereof, we have signed this specification.

GEORGE T. JOHNSON.
HARRY W. STERTZBACH.
